UNITED STATES PATENT OFFICE.

GUSTAV WILLIUS, JR., OF ST. PAUL, MINNESOTA.

MOTOR-EXTENSION RECEPTACLE.

No. 851,581.

Specification of Letters Patent.

Patented April 23, 1907.

Application filed June 23, 1905. Serial No. 266,546.

To all whom it may concern:

Be it known that I, GUSTAV WILLIUS, Jr., a resident of St. Paul, Ramsey county, Minnesota, have invented a certain new, useful, 5 and Improved Motor-Extension Receptacle, of which the following is a full, clear, and exact description, such as will enable others skilled in the art to which it appertains to make and use the same.

10 My invention relates to improvements in separable electric terminals for electric connectors, and has special reference to improvements in electrical connector plugs and sockets or receptacles therefor, for use in 15 coupling electrical devices of portable or semi-portable nature to fixed electrical conductors of electricity.

The object of my invention is to provide a 20 plug or receptacle of the class mentioned which shall be capable of employment in connection with either two or three wire circuits.

Another object of the invention is to provide a multiple terminal connector, comprising a plug and a receptacle of such form and 25 arrangement of parts as to limit the same to a predetermined relation; and absolutely prevent a reversal of polarity in the connected circuits, through faulty manipulation of said plug.

30 Still another object of the invention is to provide a connector of the class described that shall be of simple and durable construction and which shall be effectively guarded against short-circuiting, and which, furthermore, shall be of great capacity and also highly efficient.

Another object of my invention is to provide an electric terminal connector which shall be adapted for either indoor or outdoor 40 use.

Other objects of my invention will appear hereinafter.

My invention consists generally in a multiple terminal electric connector comprising a 45 plug and receptacle of the form, construction and combination of parts hereinafter described and particularly pointed out in the claims.

The invention will be more readily understood by reference to the accompanying drawings, forming a part of this specification, and in which

50 Figure 1 is a plan view of the receptacle or socket portion of my invention, the casing thereof being broken away, to show the terminal blades or springs which constitute the

socket proper; Fig. 2 is an end view of the receptacle, a portion of the end plate being broken away to disclose the interior of the receptacle; Fig. 3 is a side view, showing my 60 novel plug in position within the receptacle, the side of the casing being broken away for purposes of illustration; Fig. 4 is a sectional detail of the plug portion of my device, and Fig. 5 is a transverse section of the plug on 65 the line $x-x$ of Fig. 4.

I have designed the device illustrated in the drawings to serve electric apparatus that is operated from circuits carrying potentials or tensions up to six hundred volts and for 70 both alternating and continuous current uses, the parts being proportioned accordingly.

It will be understood that the proportions of my device, and to a certain extent, the 75 relations of the parts, will be modified to suit different requirements.

It will be understood that in general practice the permanent or fixed conductors may be connected to the terminals of the receptacle, and that the plug furnishes the terminals for the portable or semi-portable circuit, including such translating devices as motors, 80 electric lamps or storage batteries.

Referring now to the drawings, 2, represents a metal base plate or frame, upon which a block of insulating material 3, such as slate, is secured by screws, 4. The rear end or top of the frame, 2, is provided with a semicircular end, 5, perpendicular to the 90 plate and preferably integral therewith. The portion, 5, is provided with a shoulder, 6, to receive a metal casing, 7, further described hereinafter. At the front or lower end of the frame and secured to the plate or to the end 95 of the block, 3, is a semicircular plate, 8, of insulating material, having a substantially triangular opening, 9. The casing, 7, compresses a sheet or band of metal that is formed around the semicircular ends of the 100 receptacle. A sheet of asbestos forms an insulating lining for the casing and both parts are firmly bound in place by screw devices provided at the sides of the frame, 2. I prefer that these devices shall comprise small 105 brackets, 7', attached to the casing, 7, together with screws, 10, that are swiveled upon the plate, 2. The brackets, 7', are notched as shown in Fig. 1, and nuts, 10', on the screws, 10, serve to bind the casing, 7, 110 upon the semicircular ends of the receptacle frame. When the nuts, 10', are loosened,

the screws, 10, may be disengaged from the brackets, 7', and the casing with its asbestos lining may be quickly removed for access to the electrical connections within the receptacle. The end plate, 5, is provided with an insulating bushing or bushings, 5', through which the electrical conductors, A', B', C', enter the receptacle.

The receptacle or socket proper is erected upon the insulating block, 3, and has its free end extending through the triangular opening in the insulated end or diaphragm, 8. The principal members of the socket are three spring blades which occupy positions that conform to the three sides of a triangle, as best shown in Fig. 2. For a purpose hereinafter referred to, the base of the triangle thus formed is of greater length than either of the sides thereof. This determines the inclination of the blades B and C, with relation to each other and the blade A.

All of the blades are provided with outwardly turned ends to facilitate the entrance of the hereinafter described plug, and each blade has an intermediate crimp or inward bend, A³, B³, C³, the office of which is to retain said plug. The blade, A, is provided with an additional inward bend, A², near its inner, fixed end, serving as a stop for the plug. The lower blade, A, is parallel with the block, 3, and its inner end is secured to a metal block, 11, that is attached to block, 3, and provided with a terminal piece, 12, separably attached thereto. The fastenings for the blades, B and C, comprise blocks 13 and 14, having the angular bracket portions, 13' and 14' that are enlarged at their upper ends, to receive the inner ends of the spring blades, B and C, respectively.

As shown the blades, A, B and C, may be secured to respective blocks by screws or rivets, 15, and the blocks 13 and 14 have terminal pieces, 12' and 12'', like unto the parts, 12, on block, 11. The electrical conductors, A', B', C', have their ends soldered in the parts 12, 12', 12'', usually before the latter are fastened to respective blocks.

The novel plug of my invention is of simple construction.

16, is a metal tube that is threaded from end to end. This carries two triangular blocks 17 and 18 of insulating material, secured by threaded collars or nuts, 19, on said tube, 16. The contact plates, 1^A, 1^B, 1^C, are attached to the insulating blocks, 17 and 18, and bridge the space between said blocks. The plates are provided with intermediate crimps or inward bends, 20, which correspond to the crimps or bends in the receptacle springs or blades.

21, represents a handle of insulating material screwed upon the threaded tube, 16, serving also as a locking nut for all the other threaded parts on said tube. The electric wires or conductors, 22, 23, and 24 extend

through the tube, 16, and are lead out through openings, 25, therein, between the parts, 17 and 18. The ends of the wires are soldered or otherwise secured to the inner sides of respective contact plates.

It will be noted that the triangular arrangement of the contact plates on the plug corresponds to the arrangement of the spring blades of the socket, and it is evident that as the triangle formed is of irregular shape, the plug can be inserted in the socket in only one position. By this simple arrangement of parts I am able to prevent accidental or intentional misuse of the plug, which would otherwise result in the reversal of polarities in the circuit represented by the plug.

My plug has the distinct advantage of being adjustable, in the sense that its spring blades may be given any desired degree of bow by moving the insulating block, 17, inward or outward upon the threaded shank of the plug, through the agency of the threaded collars or nuts, 19.

Another advantage of my device is that the spring blades of the socket or receptacles, being disposed in triangular form, exert pressure toward a common center and thus tend to maintain uniform contact with the plates of the plug throughout.

It is obvious that the gist of my invention, to-wit, the triangular form and arrangement of the socket and plug, is capable of embodiment in numerous forms. Further the socket may be arranged in a casing of greater size than here shown and containing other electrical devices and generally as various modifications of my invention will readily suggest themselves to one skilled in the art I do not confine the invention to the specific constructions herein shown and described.

Having thus described my invention I claim as new, and desire to secure by Letters Patent:

1. In a device of the class described, a socket comprising three relatively triangularly positioned spring blades and a suitable insulating support, all of said blades having intermediate crimps and one thereof being provided with an inward bend or stop portion, in combination with a plug comprising suitably connected triangular blocks and contact plates, provided with intermediate crimps, upon the sides or faces of said blocks and suitably insulated, substantially as described.

2. In a device of the class described, a socket or receptacle comprising triangularly disposed spring blades and an insulating support therefor, in combination with a plug comprising an insulating body, three contact plates triangularly disposed thereon and means for adjusting the bow of said plates, substantially as described.

3. In a device of the class described, a suitable frame having an end, 5, in combination

with a corresponding insulating end, 8, a casing conforming to said ends, an insulating lining for said casing, means for detachably securing said casing upon said frame, and 5 socket members suitably insulated within the inclosure formed by said frame, said ends and said casing, substantially as described.

4. In a device of the class described, a suitable frame having an end, 5, in combination 10 with a corresponding insulating end, 8, a casing conforming to said ends, an insulating lining for said casing, means for detachably securing said casing upon said frame, and three triangularly disposed spring blades 15 suitably supported and insulated upon said frame with their ends extending through said insulated end, substantially as described.

5. In a device of the class described, a suitable frame, in combination with an insulating block upon said frame, suitable ends for 20 said frame, the latter having a triangular opening, a casing detachably secured to said frame, and triangularly disposed spring blades attached to said insulating block, and 25 having their ends extending through said triangular opening in the end, substantially as described.

6. In a device of the class described, a suitable frame in combination with an insulating 30 block thereon, a closed end member on one end of said frame and an end member of insulating material provided with a suitable opening on the opposite end, socket members provided upon said block, and a casing 35 having an insulating lining conforming to said ends, and means upon said frame for binding said casing upon said ends, substantially as described.

7. In a device of the class described, an 40 insulating block or support, in combination with a spring blade, A, attached thereto, angular blocks attached to said insulating support, a pair of spring blades B and C attached to said angular blocks and angularly 45 disposed with reference to said blade A, substantially as described.

8. In a device of the class described, an

insulating block or support, 3, in combination with a blade A, having a crimp or bend, A', and a stop bend, A², blades, B and C, each 50 provided with a crimp or bend, and suitable means for supporting said blades, A, B and C, in triangular relation, upon said block, 3, substantially as described.

9. In a device of the class described, a plug 55 comprising a threaded tube, in combination with triangular blocks of insulating material adjustably secured upon the said tube, suitable crimped contact plates attached to said block, and a suitable handle, substantially 60 as described.

10. In a device of the class described, a threaded tube, 16, provided with openings, 25, in combination with insulating blocks, 17 and 18, adjustably arranged upon said 65 threaded tube, contact plates arranged upon the sides of said blocks and extending therebetween and a suitable handle arranged upon said threaded tube, substantially as and for the purpose specified. 70

11. In a device of the class described, a metallic frame, in combination with a block of insulating material thereon, a pair of metal blocks attached to said insulating block and provided with angular portions, a third 75 metal block interposed between said metal blocks and attached to said insulating block, and spring blades attached to said angular portions and said interposed block respectively, one of said blades being provided with 80 an inward bend or stop portion, substantially as described.

12. In a device of the class described a triangular member, provided with an insulating handle, and having an adjustable contact plate upon each side of said triangular member, substantially as described. 85

In testimony whereof, I have hereunto set my hand, this 13th day of June, 1905, in the presence of two subscribing witnesses.
